CABINET HAVING OPEN-SIDED DRAWERS

Theodore Bailey, Habana, Cuba

Application August 6, 1946, Serial No. 688,602

1 Claim. (Cl. 312—149)

1

This invention appertains to improvements in kitchen cabinets and the like generally, and has for its primary object to widen the field of utility of the dispensing unit type of cabinet as disclosed in my Patent No. 2,432,494.

Another object of the invention has to do with the provision of a complete, attractive, and compact, form of kitchen cabinet which affords maximum convenience and usefulness in places where the absence of pantry facilities and economy in space are important considerations and whereby labor, on the part of the housewife, is reduced to a minimum by a concentrated and quickly accessible arrangement of substantially all the adjuncts, materials, and utensils, usually employed for culinary purposes and other associated operations.

Another object of the invention lies in the provision of the cabinet as hereinbefore characterized and certain accessories therefor which greatly facilitate the performance of the household duties of the housewife, particularly in the kitchen and in connection with culinary and associated operations therein, such as a flat, extensible, and reversible member, constituting a cutting surface in its normally disposed position and a work table when extended and reversed; several drawers divided into compartments to receive table linens, towels, utensils, and the like, with certain of them provided with shelves to support supplies of condiments, cleaning materials, flavorings, seasonings, etc.; hinged side leaves or shelves, with a folding stool associated with one or both of the same, for use in the preparation of menus, shopping lists, and the like, or for the support of dishes and utensils in use; and a holder for a cook-book or the like, with means to retain the book in an open position; all of these in addition to those accessories and conveniences incorporated in my aforesaid dispensing unit cabinet.

With the foregoing and other objects and advantages of equal importance in view, the invention resides in the certain new and useful combination, construction, and arrangement of parts, as will be hereinafter more fully described, set forth in the appended claim, and illustrated in the accompanying drawings, wherein:

Figure 1 is a front elevation of the improved cabinet, in accordance with my invention and with the closure of the top part disposed in its open position;

Figure 2 is an enlarged, transverse, vertical section, taken through the line 2—2 on Figure 1, looking in the direction of the arrows, and showing the work table in its extended position and

2

the cook-book holder disposed at the reading position;

Figure 3 is an enlarged, longitudinal, vertical section, taken through the line 3—3 on Figure 2, looking in the direction of the arrows;

Figure 4 is an enlarged, horizontal section, taken through the line 4—4 on Figure 1, looking in the direction of the arrows, and showing the top drawers of the base part of the cabinet in open positions to support the work table in its extended position of use;

Figure 5 is a sectional view similar to that of Figure 4, but taken through the line 5—5 on Figure 1, looking in the direction of the arrows;

Figure 6 is another sectional view similar to Figures 4 and 5, but taken through the line 6—6 on Figure 1, looking in the direction of the arrows;

Figures 7, 8, and 9 are perspective views of the central, left and right hand drawers, respectively, in the lower portion of the base part of the cabinet, and showing the arrangement of compartments and shelves within the same;

Figure 10 is a fragmentary, transverse, vertical section, through the top part of the cabinet, and showing the front closure thereof in partly opened position and the cook-book holder in its normal position of rest;

Figure 11 is a fragmentary, horizontal section, taken through the line 11—11 on Figure 10, looking in the direction of the arrows, and showing the cook-book holder in top plan; and,

Figure 12 is an enlarged, fragmentary, longitudinal, vertical section, taken through the line 12—12 on Figure 2, looking in the direction of the arrows, and showing the manner of housing the foldable and sliding sections of the front closure within the upper end of the top part of the cabinet, when the closure is moved to open position to give access to the interior of said cabinet part.

Referring to the drawings in detail, wherein like characters of reference denote corresponding parts throughout the several views, the invention, as it is exemplified therein, is embodied in a modified form of cabinet from that disclosed in my aforesaid application and is comprised in a base part A and a top part B; the parts being of the same length but the top part B is made narrower than the base part A and rises from the latter with its front side set inward from the like side thereof.

The base and top parts A and B are both rectangular in form and the base part is made with a main top wall 10, a back wall 12, side walls

14, and a bottom wall 16. The bottom wall 16 is supported on casters 20 set in short legs 18. Secured on the under side of the bottom wall 16 is a rectangular frame 22 having an area to enclose that area of the bottom wall lying within the legs 18; the frame having a depth substantially equal to the length of the latter. Loosely fitted within the frame 22 is a second frame 24 to rest on the floor to prevent accumulations of debris and dust beneath the cabinet, without interfering with movement of the cabinet from one place of use to another, the loose fit of the second frame 24 permitting it to slide freely along the floor during such movement. Positioned alongside each of the legs 18, at the front side only of the base part A, is a stop device 26, such as is commonly employed to hold doors in open or partly open position, to secure the cabinet against accidental displacement from a set position, such as might otherwise occur by reason of its being supported on the casters 20.

The base part A is provided with two intermediate horizontal walls 28 and 30, the uppermost wall 28 being positioned below the top wall 10 to provide a relatively shallow space to house a work table 32, which is hingedly connected, by means of pivoted links 34, to a follower 36 that is slideable in said space and on metal guides 38; while the lower wall 30 is positioned at a somewhat greater distance below the wall 28 to provide a larger space to house a pair of drawers 40 and 42, arranged in side-to-side relation and supported for sliding movements on metal guides 44, mounted on the side walls 14 and a centrally disposed division wall 14a.

The work table 32 is adapted to be projected outwardly of the front side of the base part A and to be supported in horizontal position upon the drawers 40 and 42, which are moved to open positions for the purpose, in which position, the table is generally useful, particularly in the preparation of foodstuffs and as a kneading board. By means of the link connections 34, the table 32 may be folded over from its projected horizontal position to rest upon the top wall 10, at the front of the cabinet top part B, for the use of its reversed side as a cutting board or the like, by which arrangement, the top side of the table remains smooth and unmarred from knife cuts and the like.

As best shown in Figure 5, the drawer 40 is provided with at least two vertical partitions 40a and 40b, to divide its interior into parallel compartments of substantially equal area, to receive tableware, culinary implements, or the like; while the drawer 42 is provided with but a single vertical partition 42a, to divide its interior into two compartments, also of substantially equal area, one of which is provided at its front end with a transversely disposed channel member 42b, such as a pencil trough or the like. Each drawer 40 and 42 is provided with a pull element 46, which is preferably in the form of an elongated strip, of a length substantially equal to that of the front wall on which it is mounted, the strip having its top and bottom sides inwardly beveled to insure of its being firmly gripped by the fingers of the user.

The space below the lower intermediate wall 30 is divided by vertical transverse partitions 14b and 14c, to provide three compartments of unequal area and to receive drawers 48, 50, and 52, the drawer 48 occupying the larger central compartment, the drawer 50 the next largest compartment, and the drawer 52 the smallest

compartment. The central drawer 48, as best shown in Figure 7, is comprised in a bottom wall 48a, a front end wall 48b, and a rear end wall 48c, which leaves its sides open for purposes to be presently explained. The space between the front and rear end walls is divided, by a vertical partition 48d, to form two main compartments of unequal area and these are subdivided, by horizontal partitions 48e and 48f, into upper and lower compartments. The upper of the smaller compartments, to the left of the partition 48d, is itself divided into substantially equal parts, by a transverse vertical partition 48g, and one of these, in turn, is divided into several relatively small elongated compartments, by a series of parallel vertical partitions 48h, which partitions are of a height approximately equal to one-half of the depth of said compartment; while the upper of the larger compartments, to the right of the partition 48d, is provided with a relatively narrow shelf 48i, of substantially U-form in plan, which extends about and is supported on the front and rear walls 48b and 48c and the partition 48d, substantially in the plane of the top edges of the partitions 48h, in the adjacent of the smaller compartments to the left of the partition 48d. The shelf 48i may be employed to support bottles or packages which are retained thereon, against accidental displacement during opening and closing movements of the drawer, by a flange 48j, rising from and extending about the free edges thereof. Also, upstanding flanges 48k are formed on the edges of the bottom wall 48a, at the open sides of the drawer, to prevent accidental displacement of articles placed within the lower compartments. The drawer is supported on metal guides 48l, one part of which is secured along the outer edges of the horizontal partitions 48e and 48f. A pull element 48m is provided on the front wall 48b, and is in the form of a strip extending horizontally thereof, with its ends projecting beyond its side edges sufficiently to overlap one-half of the thickness of the vertical partitions 14b and 14c.

The drawer 50, to the left of the centrally disposed drawer 48, is comprised in a bottom wall 50a, a front wall 50b, a rear wall 50c, and one side wall 50d, the opposite side of the drawer being open. The interior of the drawer 50 is divided by a horizontal wall 50e, disposed in the same plane as the horizontal walls 48e and 48f, of the drawer 48, to provide an upper and a lower compartment. Here, the upper compartment is provided with a substantially U-shaped shelf 50f, extending about the front, rear and side walls 50b, 50c, and 50d, the free edges of which are formed with upturned flanges 50g, to prevent accidental displacement of articles placed on the shelf. This drawer is also supported within the base part A on metal guides 50i, one part of which is secured along the outer edge of the horizontal wall 50e and another on the outer side of the side wall 50d, with the companion parts mounted on the opposite surfaces of the left side wall 14, of the base part A, and the vertical partition 14b. The edge of the bottom wall 50a, at the open side of the drawer 50, is also provided with an upturned flange 50h, while the front wall 50b carries an elongated pull element 50j which has its right hand end projecting beyond the right hand side of the drawer to overlap the other one-half of the thickness of the vertical partition 14b, in line with the pull element 48m of the drawer 48.

The drawer 52, to the right of the centrally disposed drawer 48, is made up of a bottom wall 52a, a front wall 52b, a rear wall 52c, and a side wall or portion 52d, with its interior divided into upper and lower compartments by a horizontal wall 52e, the latter being preferably disposed in a plane slightly above that occupied by the like walls of the drawers 48 and 50. An elongated pull element 52h is provided on the front wall 52b to match up with the like pull elements of the drawers 48 and 50. Also, the bottom wall 52a is provided with an upturned flange 52f extending along its edge at the open side of the drawer 52, and the drawer is supported for opening and closing movements on metal guides 52g, one part being secured along the side edge of the horizontal wall 52e and another on the outer side of the side wall 52d, with the companion parts mounted on the opposite surfaces of the right hand side wall 14, of the base part A, and the vertical partition 14c.

The top part B of the cabinet is comprised in a top wall 54, a back wall 56, and side walls 58, its front side being open and inset from the front side of the base part A, and the lower also open to engage over a pair of transversely disposed bars or cleats 60, secured in properly spaced relation on the top wall 10 of the base part, which bars or cleats serve to retain the top part in place.

A closure is provided for the open front of the cabinet part B, and is comprised in a lower section 62 and an upper section 64, hinged in edge to edge relation with the lower section, as at 66, and at its upper edge to a horizontally disposed follower 68; the two sections being dependingly supported from the follower, when in closed position. The follower 68 is supported for horizontal sliding movements within the upper portion of the cabinet part B, immediately below the top wall 54 and above the horizontal portions of guide channel elements or tracks 72, which have vertical portions extending downwardly just within the open front and at opposite sides thereof. The tracks 72 are secured on the side walls 58 and the upper ends of the vertical portions thereof curve into the horizontal portions, as best shown in Figures 2 and 10. The lower end of the lower closure section 62 is provided with a pair of rollers 74, one mounted on each of its side edges and engaged in the adjacent of the tracks 72, while a hand grip 76 is provided on the front side of the upper closure section 64 and is in the form of an elongated strip extending lengthwise of the section, the upper and lower sides of the same being inwardly beveled to insure a firm hold for the fingers.

The closure is moved to open position by initially pulling outwardly on the hand grip 76 to cause the lower section 62 to move upwardly and into folded relation with the under side of the top section, the lower end of the lower section pivoting on the rollers 74 and the hinges 66, while the rollers move upwardly of the tracks. At the end of the upward movement of both closure sections, they are folded in a horizontal position ready to be slid inwardly of the upper portion of the cabinet part, which is to be accomplished by pushing inward on the same to that end. In the inward movement of the closure sections, the follower 68 takes position against the back wall 56 and the rollers traverse the horizontal portions of the tracks 72 rearwardly of the cabinet part. When housed within the cabinet part B, the hand grip 76 abuts the front

edge of the top wall 54 thereof and in centered relation with respect to its opposite ends, lending symmetry to the arrangement of the hand grips of all of the other movable parts of the base section A.

The top part B has its interior provided with substantially the same dispensing, measuring, and mixing, equipment as that of the like part of the cabinet disclosed in my aforesaid application, the same consisting of a horizontally disposed rack 78, secured in place on the back wall 56 and one of the side walls 58, to support, for instance, a flour sifter 80, a coffee dispenser 82, a sugar dispenser 84, a flour dispenser 86, and a dispenser 88 for a liquid.

Mounted on the inner side of the opposite side wall 58 is a stand having a vertical hollow standard 90, having its front side provided with a plurality of vertical slots 92, arranged in vertical alignment, for the insertion therein of carving knives and the like, and several trays 94, arranged in vertically spaced relation, to support other articles, such as tableware, or the like.

Extending inwardly from each of the side walls 58, one in line with the other, is a pair of bracket arms 96 to the free ends of which are right angularly disposed bars 98, arranged parallel to each other and extending transversely of the interior of the cabinet part B and above the rack 78. These bars 98 are identically slotted horizontally, as at 100, with their forwardly directed ends inclined in an upward direction. A rest 102, of substantially tray-like form, is positioned between the bars 98 to support a cook-book (not shown) and a leaf holder 104 within the rest; the latter preferably being made from a length of heavy gauge wire, bent substantially U-shape, with its arms directed toward the rear side of the rest and the ends thereof out-turned to project through the side walls of the latter and slidably engage in the slots 100. When not in use the rest 102 is supported horizontally between the bars 98 and, when put to use, is moved to the front ends of the bars where it tilts to an inclined position by reason that the angled ends of the leaf holder 104 riding upwardly of the inclined ends of the slots 100 and pivoting therein for the purpose.

If desired, a drop-leaf 106 will be hinged to each side wall of the base part A, to provide additional work supports.

Having thus fully described a preferred embodiment of my invention, it is to be understood that the words which I have used are words of description rather than of limitation, and that changes may be made within the purview of the appended claim without departing from the true scope and spirit of my invention in its broader aspects.

What I claim is:

A kitchen cabinet comprising a box-like casing having vertically disposed walls and an open front, a guide element arranged on the inner surface of each of the vertically disposed side walls, a plurality of spaced parallel vertically disposed partitions arranged in said casing and coacting with said walls to define compartments, a guide element arranged on each of said partitions, drawers slidably arranged in said compartments, said drawers being each provided with an open side, a vertically disposed side portion, and a horizontally disposed wall intermediate its bottom and top, a guide element on each of said vertically disposed side portions, a guide element arranged on the free edge of each of said hori-

horizontally disposed walls and coacting with the guide element on each of said partitions, the guide elements on the side portions coacting with the guide elements on the vertically disposed side walls of said casing.

THEODORE BAILEY.
